ADJUSTABLE DISPENSER CAP FOR MAGNETIZABLE PARTICLES

Phillip J. Parker, 1710 Pinehurst Road,
Dunedin, Fla. 33528

Filed Mar. 13, 1974, Ser. No. 450,934

Term of patent 14 years

Int. Cl. D9—07

U.S. Cl. D9—257

FIG-1

FIG-2

FIG-3

FIG-4

FIG-5

FIG-6

FIG. 1 is a perspective view of an adjustable dispenser cap for magnetizable particles showing my new design;

FIG. 2 is a left side elevational view;

FIG. 3 is a front elevational view;

FIG. 4 is a rear elevational view;

FIG. 5 is a bottom plan view; and

FIG. 6 is a top plan view.

I claim:

The ornamental design for an adjustable dispenser cap for magnetizable particles, as shown.
